TRUSTEE, OF DETROIT, MICHIGAN, A CORPORATION OF MICHIGAN.

ELECTRIC-CONTACT THERMOSTAT.

1,316,361.

Specification of Letters Patent. Patented Sept. 16, 1919.

Application filed January 19, 1918. Serial No. 212,803.

To all whom it may concern:

Be it known that I, HARRY G. GEISSINGER, a citizen of the United States of America, residing at New York, in the county of New York and State of New York, have invented certain new and useful Improvements in Electric-Contact Thermostats, of which the following is a specification, reference being had therein to the accompanying drawings.

The invention relates to thermostats, of that type in which the electrical contact is made or broken by the lateral deflection of an arched element in co-operation with a chord or tie element having a different coefficient of expansion. It is the object of the present invention to overcome certain defects of constructions of the type heretofore devised and to render the instrument more sensitive and accurate in its operation and simple in its construction. The invention therefore comprises various features of construction as hereinafter set forth.

In the drawings:

Figure 1 is a longitudinal section through the instrument;

Fig. 2 is a side elevation thereof; and

Fig. 3 is a plan view.

The principle on which the construction is based is the deflection of the arch element by differential expansion due solely to the temperature which is to be controlled. Accuracy is therefore only obtained where there is freedom for movement without frictional or other resistance; where the expandable elements are exposed to free contact with the air; and where the temperature of these elements is unaffected either by independent heat generation or conduction to or from contacts other than that of the air. I have closely approximated the ideal condition,—first, by eliminating friction and providing perfect freedom of action without mechanical restraint; second, by providing full exposure to the air of all the surface of the expandable elements, avoiding any shielding of the one by another; third, by providing sufficient area and mass in the element which forms a portion of the electrical circuit to quickly dissipate whatever heat is electrically generated; fourth, by interposing thermal insulation between the elements and the base on which they are

mounted to avoid transfer of heat from the one to the other; fifth, by providing a linkage between the elements having different coefficients of expansion, which secures accuracy in movement without necessitating a high degree of mechanical perfection.

In detail, A is a suitable base or support, B and B' are chord elements parallelly arranged in the same plane and spaced from each other, and C is the arch element arranged between the elements B and B' and in substantially the same plane and having a coefficient of expansion different from that of the chord elements. In the drawings the curvature of this arched element is greatly exaggerated for clearness in illustration, but in actual construction the lateral deflection of the arch is very slight, preferably only 1-200 of the length of the chord. Thus the elements B, B' and C are in substantially the same plane and are arranged so as to be separated from the base A a sufficient distance to give free air exposure on both sides thereof.

At one end of the base is a projecting lug D to which the ends of the elements B and B' are rigidly secured by a clamping plate E. F is a groove in the central portion of the lug D, and G is a block adjustably secured in the groove F and notched at H to form a bearing for one end of the arch element C. The bottom of the groove F against which the block G bears is parallel to the plane of the elements B and B', so that any adjustment of the block will be exactly parallel to this plane. Such adjustment is effected by a screw I engaging a threaded bearing in an angle flange E' on the clamping plate E and bearing against the block G in central alinement with the arch member C. The block is retained in its position of adjustment by a clamping screw J which passes through a plate K on the opposite side of the lug D and through a slot D' in said lug, and has a threaded engagement with the block G. When the screw is loosened the block G is free to swivel thereon and to rock on its point of contact with the screw I, thereby permitting self-alinement with the end of the element C to form a good bearing thereon.

The opposite ends of the elements B, B'

and C are connected by a yoke member L. It is essential to hold this yoke in a fixed plane, and at the same time to permit of movement in this plane to compensate for any elongation or contraction in the elements B and B'. To accomplish this without introducing frictional resistance the yoke L is coupled to the base by flexible links M, preferably attached to angle flanges B² at the ends of the elements B and B'. The element C is attached to the yoke with a self-aligning bearing formed by the V-shaped member N forming a notch for receiving the end of the arch and a pivotal connection N' between this V-shaped member and the yoke. Thus both ends of the arch are in engagement with self-aligning bearings, which insures full contact and permits of employing a relatively wide strip 10 for the element C to facilitate the dissipation of electrically generated heat and to minimize the temperature rise.

The electrical circuit is closed and opened by contact and separation of the arch element C and a co-operating contact O. This contact must be adjustable for setting the same at a predetermined initial distance from the arch member C, and it is important that it should be maintained substantially at the center of the arch in all positions of adjustment thereof. I therefore preferably arrange the contact member O upon an adjustable arm P, which is pivotally connected at Q to the member K. The free end of the member P has secured thereto a spring R which is notched to engage a screw S on the base A and operates to yieldably press the member P in a direction away from the arch. T is an adjusting screw engaging a threaded bearing in the base A and having its free end in contact with the member P, the arrangement being such that said member P may be adjusted by said screw against the tension of the spring R toward the arch member C. Also the member P being hinged at Q the member K will be adjusted longitudinally to correspond with any adjustment of the block G.

To prevent heat conduction to and from the base A through the connections between the same and the elements B and B', thermal insulation is employed in such connections. Thus, as shown, the links M have arranged between the same and the base an insulating material U, and there is arranged between the lug D and the elements B and B' the thermal insulation V. These insulating members will interpose sufficient resistance to the conduction of heat to avoid materially affecting the temperature of the expandible elements through the lag caused by the mass of metal in the base A.

The construction of the parts being as described, they are easily assembled and when assembled are adjusted or set for the desired

operation. In this setting the screw J is first loosened and the block G is adjusted by operation of the set-screw I until the desired deflection or curvature of the arch member C is obtained. During this adjustment the block G is free to rock on the screw I so that its V-shaped notch H will be aligned with the edge of the end of the member C, and a similar self-alignment will take place between the V-shaped member N and the opposite end of the arch member. The adjustment of the screw I will also longitudinally adjust the member P by reason of its hinged connection Q with the block K and screw J, thereby maintaining the contact O substantially at the center of the arch. The screw J is then tightened to clamp the blocks G and K in their adjusted positions, after which the screw T may be adjusted to obtain the desired spacing between the contact O and the arch, according to the temperature at which the circuit is desired to close.

In operation the air of the room in which the instrument is located is free to come into contact with both faces of each of the elements B B' and C, and as these elements are in substantially the same plane they will not in any way shield or interfere with each other. When there is a change in temperature causing either expansion or contraction of the elements B and B' the yoke ends of said elements are free to move relative to the base in their common planes by the flexing of the link M. On the other hand, a differential expansion of the arch member C relative to said elements B and B' can only result in a lateral deflection or change in curvature of the arch so as to adjust the same into or out of contact with the contact member O. When contact is established whatever heat is electrically generated will be quickly distributed by conduction and dissipated through the large air-exposed surface of the member C. As a consequence the opening and closing of the electrical circuit will correspond accurately to predetermined temperature changes in the air which bathes the elements B B' and C.

What I claim as my invention is:

An electric contact thermostat, comprising an arch element, a pair of chord elements arranged on opposite sides thereof and in substantially the same plane, a mounting or base for said elements having a pair of lugs projecting therefrom, to which the corresponding ends of said chord elements are secured, a yoke connecting the opposite ends of said chord elements, a flexible link connecting said yoke to said mounting maintaining the plane of said elements while permitting longitudinal adjustment in said plane, a block forming a bearing for the opposite end of said arch element arranged between said lugs and having a bearing on

said mounting parallel to the plane of said elements, a screw for adjusting said block to alter the curvature of the arch, a coöperating electrical contact member, an arm on which said coöperating contact member is mounted, a connection between said arm and said bearing for the arch element for com-

pelling a corresponding adjustment thereof, and means for laterally adjusting said arm in relation to said mounting to vary the space between the same and said arch element.

In testimony whereof I affix my signature.

HARRY G. GEISSINGER.
